UNITED STATES PATENT OFFICE.

GUILLERMO LINLAUD, OF BUENOS AIRES, ARGENTINA.

LOCK.

1,301,466.

Specification of Letters Patent. Patented Apr. 22, 1919.

Application filed September 24, 1917. Serial No. 192,891.

To all whom it may concern:

Be it known that I, GUILLERMO LINLAUD, a citizen of France, residing at Buenos Aires, Argentina, have invented a new and 5 Improved Lock, of which the following specification is a full disclosure.

This invention deals with locks and it proposes certain improvements simplifying the construction thereof and permitting each 10 lock to be individually adjusted or regulated so as to function only through its own key.

To enable others skilled in the art so fully to comprehend the underlying features 15 thereof that they may embody the same by the numerous modifications in structure and relation contemplated by this invention, drawings depicting a preferred form have been annexed as a part of this disclosure, 20 and in such drawings, like characters of reference denote corresponding parts throughout all the views, of which:—

Figure 1 is a front elevation of the casing with the cover and key-measuring elements 25 removed, showing the locking bolt. Fig. 2 is an elevation showing the inner face of the removed cover with its key-measuring elements associated together. Fig. 3 is a section through the removed rear plate of the 30 lock. Fig. 4 is an assembly of the key-measuring or finding elements with the bolt-actuating plate removed. Fig. 5 is an elevation and Fig. 6 is a cross-section of the slotted locking element. Fig. 7 is a front 35 elevation and Fig. 8 is a section of the rotary member which carries the tumblers. Fig. 9 is an elevation and Fig. 10 is a section of the cover for the tumbler-carrier; which cover also serves as a bolt-actuator. 40 Fig. 11 is a side elevation of one of the tumblers. Fig. 12 is an outer end elevation of a tumbler. Fig. 13 is an inner end elevation of a tumbler and Fig. 14 is a longitudinal section through the tumbler. Fig. 45 15 shows a key in cooperative relation with a pair of tumblers. Fig. 16 is a rear elevation showing four tumblers in connection with an operating key. Fig. 17 is a front elevation showing the same tumblers in association with the slotted locking ring. Fig. 50 18 is a horizontal section through a lock showing the cover with its bolt-throwing stud and a pair of tumblers in operative relation with the locking ring.

55 The lock comprises a suitable casing A formed of side walls A' and a rear plate B

and a front plate 19. Within this casing, a suitable bolt 21 is arranged to slide, said bolt having a tongue 22 which may be projected for locking purposes and also having 60 a cam 20 which is adapted to coöperate with an actuating lug 9 carried by a rotatable plate or cover 7. This plate is firmly secured to a tumbler-carrier 5 which is arranged to be rotatably retained within the 65 locking-ring 1 secured firmly to the front-cover plate 19. The tumbler-carrier, together with its cover 7, forms a unit adapted to receive a series of similar tumblers C which are radially movable and project in- 70 wardly so as to expose their inner adjustable ends through a central opening D adapted to receive the cam-fins 24 of a key 23. The tumbler-carrier is provided with an annular channel d containing a number 75 of posts e for supporting a number of springs s, the free extremities of which enter apertures k in the sides of the tumblers C in such a manner as to urge these tumblers radially inward. The tumblers are slidably 80 arranged in suitable radial slots 4 provided by the carrier 5 so that their ends may project through registering-slots m in the annular stationary ring n provided by the tumbler-lock 1. When these springs s are 85 unrestrained by the opposing action of the key, they have the effect of moving the tumblers C inwardly so that the extremities of the tumblers interlock with the ring n and prevent the tumbler-carrier from being ro- 90 tated by a false key and thus preventing the lug 9 from actuating the bolt 21.

In order that the tumblers may be forced outwardly a sufficient distance to cause their notches 13 to register with the locking- 95 ring n and enable the tumbler-carrier to be rotated by a true key, and in order that the tumblers may be adjusted to fit any desired key, they are provided with adjusting means. Thus, as shown best by Fig. 14, each 100 tumbler provides a pair of J-shaped contact elements 17 seated in suitable recesses provided by the tumbler. One of each pair of recesses opens toward the rear end of the tumbler and receives a small screw 15 so 105 that, by adjusting the screw 15, the contact element 17 may be positioned to protrude any desired distance from the inner end of the tumbler.

The key 23 is provided with a series of 110 tangential fins 24 which are so cammed as to operate against the contact portions 17

and urge the tumblers into unlocking registry with the ring *n* when the key is inserted.

In order to secure a correct insertion of the key, its end is preferably apertured so that it may be received by a spring-pressed pin *o* carried by the rear plate *B*. The cover 7 and the base-plate of the tumbler-carrier are provided with openings 8 and 11 configurated in correspondence with the tangential fins of the key.

Without further analysis, the foregoing will so fully reveal the gist of this invention that others can, by applying current knowledge, readily adapt it for various applications without omitting certain features that, from the standpoint of the prior art, fairly constitute essential characteristics of the generic or specific aspects of this invention, and therefore such adaptations

should be and are intended to be comprehended within the meaning and range of equivalency of the following claim.

Having thus revealed this invention, I claim as new and desire to secure the following combinations of steps and elements, or equivalents thereof, by Letters Patent of the United States:

In a lock of the nature disclosed, a plurality of tumblers; said tumblers being provided with projecting extremities; and means for adjustably positioning said extremities.

In witness whereof I have hereunto set my hand in the presence of two witnesses.

GUILLEMMO LINLAUD.

Witnesses:

THEODORO MITTSU,
ANTONIO SEROARD.
